DISPENSING BOTTLE

Warren J. Luedtke, Racine County, Wis., assignor to S. C. Johnson & Son, Inc., Racine, Wis.

Filed Sept. 18, 1964, Ser. No. 81,785

Term of patent 14 years

(Cl. D58—6)

FIG. 1 is a perspective view of a dispensing bottle embodying my new design;

FIG. 2 is a side elevational view of the dispensing bottle illustrated in FIG. 1;

FIG. 3 is a front elevational view of the dispensing bottle illustrated in FIG. 1; and

FIG. 4 is a top plan view of the dispensing bottle illustrated in FIG. 1.

I claim:

The ornamental design for a dispensing bottle, substantially as shown.
